UNITED STATES PATENT OFFICE

ROBERT BELTON STANCILL, OF DALTON, GEORGIA

"JERKED-IN" FILLING ELIMINATOR

Application filed June 13, 1929. Serial No. 370,657.

The present invention appertains to new and useful improvements in looms and more particularly to a novel attachment adapted to eliminate "jerked-in" or "trailing" filling in the weft of conventional looms. "Jerked-in" or "trailing" filling is caused by the filling being held by the shuttle in the operation of returning to the cloth. The usual style loom having no more than the weight of the bobbin to draw the filling from the shuttle and nothing to hold the filling, therefore allows the shuttle to carry all of the slack of the filling into the cloth.

An important object of the invention is to overcome this disadvantage by providing a device automatically operable for retaining the "jerked-in" or "trailing" filling so that it cannot be woven into the cloth.

Other important objects and advantages of the invention will become more apparent to the reader after considering the invention as described and claimed hereinafter.

In the drawings:

Figure 1 represents a fragmentary side elevation of the attachment applied to a loom.

Figure 2 represents a vertical sectional view taken substantially on line 2—2 of Figure 1.

Figure 3 represents a vertical sectional view taken on a plane substantially at right angles to the plane on which Figure 2 has been taken.

Figure 4 represents a fragmentary vertical sectional view through the sliding block structure, the view being taken substantially on line 4—4 of Figure 3.

Figure 5 represents a fragmentary side elevation showing the bearing set for supporting the stroke arm.

Figure 6 represents a horizontal sectional view taken substantially on line 6—6 of Figure 3.

Figure 7 is a perspective view of the movable block mounted on the bearing set shown in Figure 5.

Figure 8 represents a cross sectional view of the block shown in Figure 7.

Referring to the drawings, wherein like numerals designate like parts, it will be seen

that the invention is adapted to be attached to the loom structure generally referred to by numeral 5 and on the battery side thereof.

The attachment includes a bracket 6 secured to the loom structure 5 by suitable elements 7 and having a protuberance 8 extending outwardly at its intermediacy. The upper end portion of the bracket is disposed outwardly as at 9, upwardly as at 10, and further outwardly as at 11. An arm 12 is secured to the protuberance 8 as at 13 and extends outwardly in substantial parallelism with respect to the extending portion 11 of the upper end of the bracket.

An inverted U-shaped guide 14 has each leg portion provided with a longitudinally extending slot 15. A trip device 16 has its upper end portion twisted as at 17 and disposed laterally as at 18 for disposition between the extending portion 11 of the bracket 6 and the bight portion of the U-shaped guide 14. A rivet 19 serves to secure these elements together in the manner clearly shown in Figure 3.

The last mentioned end portion of the device 16 protrudes beyond the bracket extension 11 and is provided with an opening to slidably receive the pawl carrying connecting rod 20, which is pivotally connected at its upper end as at 21 to the usual transferrer bar 22 of the automatic bobbin replenishing mechanism.

A stop arm 23 projects from the arm 12 and is offset at its upper end 24 and apertured to slidably receive the aforementioned rod 20. The lower end portion of the rod is reduced as at 25 and provided with a cross pin 26 in its extremity, while the intermediate portion 27 is provided with threads on which the pawl 28 is adjustable and adapted to be fixed in a definite position by the cam nut 29, also movable on the threaded portion of the rod.

The lower end of one of the legs of the U-shaped guide 14 is secured to the free end of the arm 12, while projections 30—30 project laterally from the lower ends of the legs and are converged inwardly at their free ends for attachment to the lower end of the trip device 16, as at 31.

Slidably disposed within the U-shaped guide 14 is a block 32, the strap 33 engaged over its top and along the sides thereof adjacent the legs of the guide. A substantially U-shaped frame 34 has its leg portions secured to the top and bottom of the block 32, and is apertured at its bight portion to slidably receive the stem 35 of a bolt 36, which bolt is slidably disposed through an opening 37 extending transversely through the block 32.

10 A compressible coiled spring 38 is interposed between the bight portion of the frame and the bolt 36 for normally maintaining the bolt projected to the position as shown in Fig. 3. The free end portion of the stem 35 is guided by the guide device 16 and it will be seen that the intermediate portion of the device 16 gradually flares upwardly as at 38 to the shoulder 39, so that as the aforementioned trigger block moves upwardly, the stem 35 will gradually feed to compress the spring 38 and retract the bolt 36.

In Figure 5, the bearing set 40 is threaded at one end for disposition within a threaded recess in the loom structure 5 while its outer end portion is also threaded to receive the adjusting nut 41. A block 42 is provided on the set 40 adjacent the loom structure 5 and is provided with an angularly disposed face 43 against which the adjacent end of the block 44 is adapted to wipe when moved. The nut 41 is adapted to be fed against the washer 45, which in turn compresses the spring 46 against the movable block 44.

25 The end portion of the spring 46 adjacent the block 44 has an extension 47 which engages around the arm 49. The arm 49 is bent laterally as at 50 and obliquely as at 51 in acute angular relation to the portion 50. 40 A pin 52 is disposed between the lower end portions of the strap 33 and a block 53 rotatably mounted thereon. A pintle 54 depends from the block 53 and is pivotally connected as at 55 to the rod 56, which rod is threaded as at 57, its lower end portion.

45 An angle member 58 is provided with an eye 59 at one end for receiving the threaded portion 57 of the rod 56 and nut 60 on the threaded portion of the rod 56 serves to adjustably secure the eye 59 at a predetermined position on the rod.

The depending portion of the angle member 58 is disposed through the apertured free end of the portion 51 of the arm 49. Thus a 55 swivelled connection is provided between the arm 49 and the rod 56. The aforementioned block 44 is provided with grooveways 61 which received the secured end of the arm 49, while the other is adapted to receive the secured end of the arm 62, which arm is provided at its free end with the serrated filling engageable blade 63. The blade 63 is disposed laterally for contact with the chute 64 of the bobbin replenishing mechanism.

65 It will be seen that the downward stroke

of the transerrer arm 22 will cause the downward movement of the rod 20 and the slipping by of the pawl 28 past the bolt 36. The tension of the spring 46 will snap the filling engageable blade 63 against the trailing filling where it will remain until the transerrer arm 22 moves upwardly. As the arm 22 travels upwardly, the pawl 28 engages beneath the outer end of the latch 36 and moves the trip carrying block upwardly within the guide 14. The pawl 28 will remain abutting the bolt 36, until the slotted end portion of the stem 35 has been moved sufficiently by the inclined disposition of the portion 38 of the device 16 so as to disengage the bolt 36 from the pawl 28.

70 The trip will then descend within the guide 14 to the position shown in Figure 4, thus swaying the filling engageable blade against the chute 64.

75 It will thus be seen that the present device is substantially automatic in operation and depends upon movements of the transerrer arm or some other similar operating feature of the loom, and it is to be further understood that this attachment may be connected to various types of looms, various changes in the specific shape, size and materials may be resorted to without departing from the spirit and scope of the invention as claimed herein- 80 after.

85 Having thus described my invention, what I claim as new is:

1. A machine for looms comprising a filling engageable arm, a trip mechanism, means interposed between the trip mechanism and the usual transerrer arm of the bobbin replenisher, and a connection between the trip mechanism and the said filling engageable arm whereby the arm may be moved to engage the trailing filling and be released by said trip mechanism after a time interval sufficient to break the filling, said trip mechanism consisting of a spring projected plunger, and means for engaging the plunger to retract the same when the same is being moved in a predetermined position.

100 2. A machine for looms comprising in combination, a bobbin transferring mechanism, a filling engageable arm, a trip mechanism, said trip mechanism including a pawl, a rod depending from the usual transerrer arm of the bobbin mechanism, a spring projected bolt, a connection between the projected bolt and the filling engageable arm, and means for 105 disengaging the said spring projected bolt from the pawl upon a predetermined movement thereof responsive to the operation of the transerrer arm.

110 In testimony whereof I affix my signature. 115
ROBERT BELTON STANCILL.
